UNITED STATES PATENT OFFICE.

GEORGE WILLIAM HANNA, OF SARDIS, TENNESSEE.

WELL-DIGGING MACHINE.

Application filed May 8, 1923. Serial No. 637,409.

To all whom it may concern:

Be it known that I, GEORGE W. HANNA, a citizen of the United States, residing at Hinkle, P. O. Sardis, R. F. D. 2, in the 5 county of Hardin and State of Tennessee, have invented certain new and useful Improvements in Well-Digging Machines, of which the following is a specification.

In carrying out the present invention, it 10 is my purpose to provide a machine that is well adapted for digging wells in a novel, simple and expeditious manner.

The primary object of the invention resides in the provision of such a machine that 15 is not only comparatively simple of construction, but one that will embrace at the same time the desired features of simplicity, durability and high efficiency of operation, the machine comprising relatively few parts, 20 and these so correlated as to reduce the possibility of disarrangement to a minimum.

A further object of the invention resides 25 in the provision of such a machine, that is capable of being readily moved from place to place.

A still further object resides in the provision of such a machine wherein the digging element per se is provided with novel 30 means for extracting rocks, boulders or the like from the ground.

The nature and advantages of the invention will be better understood when the following detailed description is read in connection with the accompanying drawings, 35 the invention residing in the construction, combination, and arrangement of parts as claimed.

In the drawings forming part of this application, like numerals of reference indicate 40 similar parts in the several views, and wherein:

Figure 1 is a side elevation of my improved machine.

Figure 2 is a top plan view thereof, and

Figure 3 is an enlarged vertical cross section of the digging element, per se.

Referring to the drawings in detail, my 50 invention comprises a relatively elongated flat-like supporting frame 5, equipped with a rear stationary axle 6 and a front swivel axle 7 upon the ends of which are supporting wheels 8. The frame 5 is equipped with a pair of spaced vertically extending standards 9 and 10 respectively, between which 55 is journaled a cross shaft 11. Fixed upon this shaft 11 is a relatively long cable drum

12 adjacent one end of which is a spur gear 13, loose upon the shaft, there being formed at one side clutch teeth 14, which are complementary to a clutch element 15 splined upon the shaft 11 between the end of the drum and the adjacent standard 10. The opposite end of the cable drum 12 is equipped with a brake drum 16, surrounding which is a desirable form of brake band 17, that is 60 actuated by a foot pedal 18, suitably pivotally secured to the adjacent shaft standard 9.

The said clutch element 15 is provided with a grooved collar in engagement with 70 which is the yoked end of a throw lever 19, pivotally secured at 20 to the standard 10, it being of course understood that when this lever is actuated in one direction, the clutch element 15 will be engaged with the clutch 75 teeth 14 for rotating the drum when the gear 13 is rotated in a manner hereinafter set forth, for thereby operatively connecting the same to the shaft 11.

The free end of the frame 5 is provided 80 with a suitable form of freely rotatable bevel ring gear 21, which may be rotated by horse power through the medium of a laterally projecting tongue 22, that carries a single-tree 23. If desirable, this ring gear 21 may 85 be rotated through the medium of a gasoline engine or electric motor (not shown).

Extending longitudinally for a portion of the frame length is a shaft 25, journaled within standards 26 and 27 as well as the standard 10, for the shaft 11. The front end of this shaft 25 is equipped with a bevelled gear 28, which is in mesh with the said ring gear 21. Adjacent the rear end of the shaft 25, the same is equipped with a spur gear 29, 90 that is in mesh with a spur gear 30 upon a stub shaft 31 journaled between the standards 10 and 27, this last mentioned gear being also in mesh with the gear 13 of the cable drum 12, it being noted from a consideration of Figure 1, that the gears 29 and 30 95 are relatively smaller than the gear 13 for obvious purposes.

Extending upwardly and outwardly from 100 one side of the frame 5, and rigidly secured thereto is a somewhat inverted V-shaped frame 32, the upper end of which is equipped with a loose pulley 33.

Connected at one end to the drum 12 and adapted to be wound thereon is a cable 34, 110 the opposite end thereof being extended upwardly and laterally from the frame and en-

gaging over said pulley 33, and being thence connected to a digging element 35.

This digging element 35 is somewhat in the form of a bucket comprising a cylindrical open ended shell of desirable length and diameter, the upper end thereof being equipped with a bail 36 that carries a hook 37 for engagement within a ring 38 carried by the free end of the cable 34.

10 In view of the above description, it will at once be apparent that when the cable 34 is wound upon the drum 12 through the medium of animal or other power, the bucket 35 will be raised. By releasing the clutch 15 element 15 from the clutch teeth 14, the bucket 35 will drop under its own weight, and thereby embedding itself into the ground, which will when the same is raised from the ground, withdraw a portion of the 20 earth.

In Figure 3, there is shown a form of digger that is adapted to be used in conjunction with this machine, the same being associated with novel means for withdrawing rocks, boulders and the like from the ground. In this instance, the same comprises an open ended cylindrical shell 39 of desirable length and diameter, and being formed at its upper end with upwardly and inwardly extending arms 40 integral with which is a bar or rod 41. Within the shell 39 and at opposite sides thereof is a pair of grapple rods 42 that are pivoted within the shell as at 43, the upper ends 35 of these rods extending inwardly at 44, and thence upwardly at 45. The upper end of the shell 39 carries a pair of laterally inwardly extending bars 46 that are headed at their inner ends, these bars extending 40 through openings in the portions 45 of said grapple bars 42. Coiled springs 47 encircle said rods between the bucket and parts 45 of the bars 42 and normally maintaining the same in position as shown in Figure 3.

45 Freely slidable through a central opening in the cross bar 48 is a rod 49, the lower end of which carries a roller 50 that is adapted for engaging the adjacent portions 50 of the grapple bars, when the same are moved upwardly in the manner presently to be set forth. This roller 50 is normally maintained downward, out of engagement with the grapple bars, through the medium of a coiled spring 51. Secured at one end 55 to the upper end of the rod 49 is a pair of cables 52, the upper end thereof being se-

cured to a link 53 upon the end of the machine hoisting cable 34'. This ring 53 is extended through a ring 54 carried by the upper end of the element 41, it being clearly 60 noted that when this bucket is dropped in a manner similar to the bucket 35, and should there be a boulder or other obstruction within the ground, an upward movement of the bucket through the medium of the cable 34' 65 will consequently cause an engagement of the roller 50 with the upper ends of the grapple bars 42, for thereby swinging the lower ends of the same inwardly into engagement with the boulder. 70

When the apparatus is operated by horse power, the wheels 8 are removed from their axles, and the frame of the machine is lowered upon the surface of the ground. The horse is secured to the singletree 23 and 75 moved around the center of the longer bevelled gear wheel. There is ample clearance space along the intermediate portion of the shaft 25 to permit the horse to step over the said shaft as it moves in a circular path. 80

In view of the above description, it will at once be apparent that I have provided a highly novel form of well digging machine, and even though I have herein shown and described my machine as comprising certain 85 structural elements, it is nevertheless to be understood that these elements may be modified to meet different demands without departing from the scope of the appended 90 claim.

Having thus described my invention, what I claim as new, and desire to secure by Letters Patent, is:

In apparatus of the character described, the digger comprising a cylindrical shell, 95 means for hoisting the shell, grapple rods pivotally mounted within the shell at the upper portion thereof and having angularly disposed upper end portions extending toward the intermediate portion of the shell, 100 springs interposed between the shell and the upper end of the said angularly disposed portion and adapted to normally hold the lower portions of the gripper rod against the inner surface of the shell, a roller located between the angularly disposed portions of the gripper rod, and means operatively connecting the roller with the hoisting means for the shell. 105

In testimony whereof I affix my signature.

GEORGE WILLIAM HANNA.
